UNITED STATES PATENT OFFICE.

LEVI L. HEIZER, OF MUSCATINE, IOWA.

ILLUMINATED SIGN.

Application filed December 29, 1924. Serial No. 758,889.

To all whom it may concern:

Be it known that I, LEVI L. HEIZER, a citizen of the United States, residing at Muscatine, in the county of Muscatine and State of Iowa, have invented certain new and useful Improvements in Illuminated Signs; and I do declare the following to be a full, clear, and exact description of the invention, such as will enable others skilled in the art to which it appertains to make and use the same.

My invention relates to improvements in illuminated signs such as those for displaying information as to speed regulations, points of danger, etc., along highways, the invention however being also usable for other purposes.

The principal object of the invention is to provide a simple and inexpensive device in which a reflector is located at the front side of the sign for reflecting rays of light against the latter and illuminating it, said reflector having a colored translucent portion which draws the attention of passers-by thereto, so that they can not fail to read the subject matter of the sign.

A further object is to provide a simple construction by means of which the reflector may be adjusted toward and from the sign or may be entirely detached, if it is desired to use said sign without the illuminating means.

Yet another object is to provide a device of extremely simple construction which may be easily assembled or disassembled, as occasion may demand.

With the foregoing in view, the invention resides in the novel subject matter herein-after described and claimed, the description being supplemented by the accompanying drawings.

Figure 1 is an edge view of a sign constructed in accordance with my invention.

Figure 2 is a front elevation with part of the supporting standard omitted.

Figure 3 is a vertical sectional view on line 3—3 of Fig. 1.

Figure 4 is a vertical section as indicated by line 4—4 of Fig. 2.

Figure 5 is an edge view partly broken away and in section, showing a double form of the invention, whereas the preceding views illustrate a structure having only one sign.

In the drawings above briefly described, the numeral 1 designates a sign plate which

may be supported in any desired manner. For illustrative purposes, I have shown a flat disk 2 contacting with the rear side of the plate 1 and secured to it by bolts 3, said disk being connected by an elbow 4 with a vertical standard 5 formed by a length of piping. This standard or its equivalent may be held rigidly by any preferred means, a base 6 being shown therefor, which may be bolted down to or otherwise secured to a base or the like. Obviously, in addition to supporting the sign plate 1 in any desired manner, it may be of any preferred shape, although the circular outline will probably be most used.

Spaced forwardly from the sign plate 1, I have shown a reflector 7 which is preferably disposed opposite the central portion of said plate, said reflector facing the plate 75 and having a translucent, colored portion 8 which is formed of glass or other appropriate material. In the present showing, this portion 8 is carried by a cylindrical casting 9 which projects outwardly from the reflector, but this detail of construction is, of course, not essential.

An electric light bulb 10 has been shown within the confines of the reflector 7, so that this bulb and reflector will not only effectively illuminate the sign 1, but said bulb will also project rays of light through the colored transparent portion 8, so that the entire device will be very conspicuous to any persons passing by.

In the preferred form of construction I form the sign plate 1 and the disk 2 with aligned openings 11, and thread one end portion of a short pipe 12 in these openings, the other end of the pipe being provided with a suitable connection 13 secured to the reflector 7 and provided with a lateral branch 14 which contains a socket 15 for the bulb 10. Current supply wires 16 for the socket and bulb, preferably pass through the pipe 12, as shown. Thus, this pipe forms supporting means for the reflector, receiving means for the current conducting wires, and also constitute means whereby the reflector may be adjusted toward or from the sign plate 1, it being understood that the pipe is threaded for a sufficient distance to permit such adjustment. Moreover, it may here be explained that if it is desired to use the sign without the illuminating means, the pipe 12 may be entirely unthreaded from the plate 1 and disk 2. This is also done

when substituting one sign plate for another and thus this substitution may be quickly and easily made.

In Fig. 5, I have disclosed two sign plates 5 1^a disposed in parallel relation and provided with illuminating units 10^a identical with the illuminating means above described. The disk 2^a, to which the sign plates 1^a are secured, are threaded upon opposite ends of 10 a T-coupling 4^a which may well be supported by a standard or the like 5^a.

If desired, an upright rod or the like 17 may be connected with the T-coupling 4^a or with the elbow 4, to carry an arrow or the 15 like 18 which indicates the direction to be taken to reach a certain point.

It will be seen from the foregoing that while the invention is extremely simple and inexpensive, it will be highly efficient and 20 desirable for numerous purposes, particular attention being directed to the following:— The single light 10 illuminates the sign and also the colored translucent portion 8, so that the latter may be seen at a great distance and will effectively attract attention 25 to the printed matter on the sign; the reflector and light are quickly and easily adjustable toward and from the sign to obtain the best illuminating effects; these parts may be 30 quickly and easily detached if it is desired to use the sign without them or when substituting one sign plate for another; and such substitution may be quickly and easily made.

As excellent results are obtainable from

the details disclosed, they are preferably 35 followed, but within the scope of the invention as claimed, numerous modifications may be made.

I claim:—

1. An illuminated sign, comprising a sign 40 plate, a reflector supporting pipe having an adjustable connection with said sign plate, a reflector attached to said pipe, a cylindrical casing projecting outwardly from said reflector, a colored transparent portion arranged in said cylindrical casing, a lamp carried by said reflector supporting pipe between the reflector and said sign plate and in line with said cylindrical casing, whereby the transparent colored portion thereof is 45 illuminated and whereby the light rays of the lamp are thrown onto the sign by the reflector.

2. An illuminated sign comprising a standard, a disk connected with the upper end of 55 said standard, a sign plate secured to said disk, a reflector supporting pipe having an adjustable threaded engagement with said sign plate and disk, a reflector, a connection between said reflector and said pipe, said 60 connection having a lamp socket, a cylindrical casing projecting outwardly from the center of said reflector, a transparent colored portion in said cylindrical casing, adapted to be illuminated by the lamp in said socket. 65

In testimony whereof, I have hereunto affixed my signature.

LEVI L. HEIZER.
